UNITED STATES PATENT OFFICE.

JOHN C. ROOT, OF NEWCASTLE, INDIANA.

FLOUR-SIFTER.

1,085,824.

Specification of Letters Patent.

Patented Feb. 3, 1914.

Application filed June 14, 1913. Serial No. 773,785.

To all whom it may concern:

Be it known that I, JOHN C. Root, a citizen of the United States, residing at Newcastle, in the county of Henry and State of Indiana, have invented a new and useful Flour-Sifter, of which the following is a specification.

This invention relates to flour sifters and is more particularly an attachment for bins and other bulk holders.

One of the objects of the invention is to provide a sifter which can be operated readily and which has combined therewith an agitator by means of which the contents of the bulk holder are kept in motion.

A further object is to provide a sifter having no parts rubbing upon the screening or sifting fabric and which will not, therefore, tend to break up foreign substances and force them through the fabric.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a central vertical section through the bin, a portion thereof being broken away and parts of the sifter being shown in section and parts in elevation. Fig. 2 is a section on line A—B Fig. 1. Fig. 3 is an enlarged section on line C—D Fig. 1. Fig. 4 is an enlarged vertical section through the sifter on the line E—F Fig. 3.

Referring to the figures by characters of reference 1 designates a bin of any desired size and proportions, said bin being formed with a conical bottom 2 in which is fitted the sifter and agitator constituting the present invention. Ears 3 or the like are extended outwardly from the bottom 2 close to the outlet opening 4 in said bottom and bolted or otherwise secured to these ears or projections are ears 5 extending outwardly from a band 6 which extends upwardly from a main ring 7. This ring has a cross strip 8 disposed diametrically therein.

Mounted on the ring 7 is a smaller upper ring 9 to which is secured the lower edge of a cylindrical screen 10, said lower edge being bent inwardly and extending under a holding ring 11 preferably L-shaped in cross section. This holding ring is attached to the upper ring 9 in any suitable manner and reinforcing rods 12 extend upwardly from the holding ring 11 and along the inner side of the screen fabric 10. The upper portions of these rods 12 are soldered or otherwise secured to the inner surface of a conical spreader or cap 13 which is soldered or otherwise secured to the upper edge of the screen fabric 10, the rods 12 being extended inwardly from their points of attachment to the cap 13 and being connected by a knob 14 or the like located under the cap. Preferably four ears 15 extend radially from the cap 13 near the base thereof, these ears being provided with apertures 16 as shown.

Formed within the holding ring 11 is a diametrically disposed strip 17 having a central opening 18 adapted to receive the threaded end of a connecting bolt 19. This bolt extends loosely through the center of the strip 17 and also through the center of another diametrically disposed strip 20 carried by a bottom ring 21 which bears upwardly against ring 7. This bolt 19 serves to hold the rings 7, 9 and 21 assembled in proper relation to each other although permitting the rings 9 and 21 to rotate independently of the ring 7.

In order that the rings 9 and 21 may be caused to rotate together, an arm 22 is extended downwardly from the cross strip 17, this arm being extended through ring 7 and then bent laterally so as to extend radially beyond the sifter, as shown at 23; this projecting portion being formed with a knob 24 or the like whereby it can be actuated readily. The projecting portion 23 is preferably seated in a groove in the upper face of the ring 21 so that, when the extension 23 is swung to the right or to the left, ring 21 will be moved therewith as will also the holding ring 11 and the top ring 9. Agitating pins 25 are fixedly mounted adjacent their centers within the holding ring 11, the outer ends of these pins projecting into the space between band 6 and screen 10 while the inner ends of the pins project into the space surrounded by the retaining ring 11. Agitating wires 26 are soldered or otherwise secured to the walls of the bin or bulk holder.

1 close to the top thereof, these agitating devices extending downwardly along the inner surfaces of the walls and thence along the inner surface of the bottom 2 where they 5 merge into upwardly extending hooked fingers 27 which fit loosely within the ears or brackets 15, as shown particularly in Fig. 1.

It will be apparent that, when the extension 23 is reciprocated, the two rings 9 and 21 will be rotated back and forth relative to the ring 7 and, consequently the cylindrical screen 10, its cap 13, and all parts connected thereto, will likewise be moved back 15 and forth within the bottom portion of the bin. As the agitating rods or wires 26 are fixedly connected at their upper ends to the walls of the bulk holder or bin, it will be apparent that, during the back and forth rotation of the cap 13, the lower end portions or fingers 27 will be moved back and forth, thus causing the vertically extending portions of the rods or wires to swing back and forth relative to the walls of the bin, thus 25 agitating the portion of the material close to the walls and causing it to gravitate freely into the space surrounded by the band 6. The material in this space will be kept in motion by the pins 25 and will be 30 gradually worked through the screen 10, passing outwardly through the ring with the other material which has sifted through the screen. A tubular spout 28 may be extended downwardly from the lower ring 21 35 so as to facilitate the filling of bags and the like.

It will be noted that by providing a sifter such as herein described, there are no parts adapted to work upon the screen fabric 10 40 and, consequently, there is no danger of foreign substances being pulverized and forced through the screen.

What is claimed is:—

1. The combination with a bulk holder 45 having a bottom converging downwardly to an outlet opening, of a revoluble screen extending through said opening, means for supporting the screen for rotation, means for rotating the screen, a spreading cap at 50 the upper end of and revoluble with the screen, and an agitating device fixedly connected at its upper end to the bulk holder and at its lower end to the cap, said lower end being shiftable with the cap to move the 55 agitating device relative to the bulk holder.

2. The combination with a bulk holder

having an outlet in the bottom thereof, of a stationary ring, a screen extending through the outlet and above the ring, means for rotating the screen, a spreading cap closing 60 the upper end of the screen, flexible agitating devices secured at their upper ends to the walls of the bulk holder and movably connected at their lower ends to the cap, said lower ends being shiftable with the cap to swing the agitating devices relative to the walls.

3. The combination with a bulk holder having an opening in the bottom thereof, of a cylindrical screen extending upwardly 70 through the opening, said screen being open at its lower end, a cap constituting a closure for the upper end of the screen, means for rotating the screen back and forth to sift material therethrough, an agitating device secured fixedly at one end to the upper portion of the bulk holder and movably connected at its other end to the cap, said lower end being shiftable with the screen to swing the agitator relative to the bulk 75 holder.

4. The combination with a bulk holder having an opening in the bottom thereof, of an upstanding cylindrical screen mounted for rotation in the opening, said screen being open at the bottom and closed at the top, an agitating rod secured at its upper end to the upper portion of a wall of the bulk holder, and a hooked finger at the lower end of the said rod and slidably engaging the 90 closed upper end of the screen, said finger being shiftable with the screen to swing the rod, and means for rotating the screen.

5. The combination with a bulk holder having an opening in the bottom thereof, of 95 a cylindrical screen open at its lower end and mounted for rotation in said opening, means for rotating the screen back and forth to sift material therethrough, a conical cap constituting a closure for the upper end of 100 the screen, said cap being revoluble with the screen, a bracket outstanding from the cap, an agitating rod secured at one end to one wall of the bulk holder, the lower end of said rod loosely engaging the bracket.

In testimony that I claim the foregoing as my own, I have hereto affixed my signature in the presence of two witnesses.

JOHN C. ROOT.
